UNITED STATES PATENT OFFICE.

SIDNEY PLASCLASCOVITIE, OF DENVER, COLORADO.

SPOON ATTACHMENT.

1,300,008.

Specification of Letters Patent. Patented Apr. 8, 1919.

Application filed October 29, 1918. Serial No. 260,215.

To all whom it may concern:

Be it known that I, SIDNEY PLASCLASCOVITIE, a citizen of the United States, residing at Denver, in the county of Denver and 5 State of Colorado, have invented new and useful Improvements in Spoon Attachments, of which the following is a specification.

This invention has reference to an attachment for a spoon, and has for its object to 10 produce a simple means whereby a spoon may be suspended from the mouth of a vessel.

A further object of the invention is to produce an article of this character which 15 may be cheaply constructed, easily applied to the handle of the spoon and effectively retained thereon to provide a rest or support for the spoon.

Other objects and advantages will appear 20 as the nature of the invention is better understood, reference being had to the accompanying drawings, in which:

Figure 1 is a perspective view illustrating the improvement;

Fig. 2 is a transverse section through the handle of the spoon showing the improvement attached thereto, and looking downward thereon.

Fig. 3 is a perspective view of the improvement detached;

Fig. 4 is a similar view of a clamp which may be employed; and

Fig. 5 is a perspective view of a modification.

As disclosed by the drawings, the improvement comprises a body member constructed from a single piece of resilient material. The body, in plan comprises a substantially rectangular element provided, 35 however, from one of its edges with an extension, the latter designed to be bent over the body to form a suspending element or tongue 5. The body, in a line with the inner edge of the tongue is folded upon itself 40 forming spaced spring jaws 6 and 7 respectively, the jaw 6 being in a direct line with the tongue 5, that is, the tongue is formed from the portion of the body that provides the jaw 6. Both of the jaws have their 45 edges rounded upon themselves and preferably extended inwardly. The beads 8 provided by the referred to rounded portions permit of the handle 9 of the spoon 10 being readily inserted between the jaws, and the

beads are so spaced from the inner or connected portion of the jaws as to engage with one of the edges of the spoon handle.

It will be noted that as the jaws exert a tension toward each other the spoon handle will be impinged therebetween, and under 60 ordinary conditions no additional means need be employed for holding the device upon the handle. However, in some instances it may be found desirable to provide 65 additional holding means, and in the preferred embodiment of the improvement I have illustrated a wedge member or clamp comprising a substantially U-shaped element 11, either the limbs of which being 70 designed to be inserted between the jaws 6 and one of the sides or faces of the spoon handle. By reference to Fig. 2 of the drawings it will be seen that the jaw 6 is of a greater length than the jaw 7, so when the 75 wedge is in position one of the outer rounded corners thereof is contacted by the bead 8 of the jaw 6, while the inner and opposite rounded corner of the said wedge is in contacting position with the bead 8 of the jaw 7. The contacting engagement of the outer corner with the bead 8 of the jaw 6 prevents 80 the accidental outward movement or the disconnection of the wedge from the handle and jaws.

In Fig. 5 the construction is substantially 85 similar to that described, except that the tongue 12 extends outwardly from the body 13, instead of being arranged directly opposite the body as illustrated in the preferred embodiment. Also in the said Fig. 5 one of the jaws, say the jaw 14 has a threaded orifice, the threads of which being engaged by the threads of a binding element 15. The element 15 contacts with one of the 90 sides or faces of the spoon handle to effectively secure the device thereon.

Having thus described the invention, what is claimed as new, is:—

In an attachment for the handles of 100 spoons, a body constructed of spring material bent upon itself to provide oppositely disposed co-acting spring jaws designed to receive and impinge therebetween the handle of a spoon or the like, said jaws being 105 of unequal length and having their edges beaded, an angle tongue formed on one end of one of the jaws, a substantially U-shaped

binding element having one of its limbs designed to be inserted between the longer jaw and one of the faces of the handle and its second limb arranged over the shorter jaw to force the last mentioned jaw in tighter contact with the handle, and the said U-shaped member, when in such position hav-

ing one of the outer corners thereof frictionally contacted by the bead of the longer jaw to hold the said element against accidental removal from its engagement with the jaws and with the handle. 10

In testimony whereof I affix my signature.
SIDNEY PLASCLASCOVITIE.
